Primary Examiner — John A Voytek(74) *Attorney, Agent, or Firm* — Onello & Mello, LLP(57) **CLAIM**

An ornamental design for a tire, as shown and described.

DESCRIPTION

FIG. 1 is side view of a tire, in accordance with the present invention;

FIG. 2 is an isometric view of the tire of FIG. 1;

FIG. 3 is a front, rear, top and bottom view of the tire of FIG. 1;

FIG. 4 is a second side view of the tire of FIG. 1;

FIG. 5 is a cross-sectional view of the tire of FIG. 4; and, FIG. 6 is an enlarged portion of the tire of FIG. 4.

In the drawings, the broken lines illustrate environment and form no part of the claimed design.
